PETER AITCHISON, OF NEW ROCHELLE, NEW YORK, ASSIGNOR TO AMERICAN BANK
NOTE COMPANY, OF NEW YORK, N. Y., A CORPORATION OF NEW YORK.

METHOD OR ART OF AND APPARATUS FOR CONDITIONING PRINTED PAPER.

1,806,456.

Specification of Letters Patent. Patented June 10, 1919.

Application filed August 6, 1918. Serial No. 248,635.

To all whom it may concern:

Be it known that I, PETER AITCHISON, a subject of the King of the United Kingdom of Great Britain and Ireland, residing at

5 New Rochelle, in the county of Westchester and State of New York, have invented certain new and useful Improvements in Methods or Art of and Apparatus for Conditioning Printed Paper, of which the following 10 is a specification, reference being had therein to the accompanying drawings, which form a part thereof.

15 My invention relates to the method or art of, and apparatus for, conditioning printed paper, and more particularly to such a method or art, and such an apparatus, for receiving dampened sheets of paper which have received one or more impressions, and storing them preparatory to the making of 20 a succeeding impression, or impressions thereon.

25 In making imprints from planographic printing surfaces, and from engraved, intaglio, or under-surface printing plates, it has always been essential to dampen the sheets of paper in order to secure a proper impression thereupon. When two or more impressions are made upon a sheet, upon the same or upon opposite sides thereof, it has 30 been a common practice to redampen the sheets between succeeding impressions, since a certain interval of time is required for the ink to properly dry, and during this interval there is a tendency of the paper to dry and 35 to shrink by reason of the loss of moisture through evaporation. This shrinkage of the paper results in the loss of register of succeeding impressions, unless the moisture thus lost is restored by a redamping operation.

40 To avoid offsetting from one printed sheet to another, as the sheets are collected, it has also been a common practice to use insert sheets of dry tissue paper, which sheets, in actual practice, receive any offset which occurs. Furthermore, there is always a likelihood of these insert sheets slightly defacing 45 the imprint, and absorbing some of the moisture from the dampened paper, thus aggravating those conditions which necessitate redamping of the paper between succeeding 50 impressions thereon.

Repeated damping or wetting of paper also has a tendency to destroy the surface finish of the paper, and cause irregularities

therein, due to repeated expansion and 55 shrinkage before the sheet is completely printed.

By the method or art of my invention, I am enabled to collect and store the dampened sheets of paper under conditions which 60 will not only minimize, or avoid, offsetting of any description, but will prevent the evaporation of moisture from the dampened sheet to an extent to admit of the making of 65 a number of succeeding impressions upon the same sheet of paper without the necessity for redamping the paper. Furthermore, each sheet of paper, after each impression thereon, is subjected to pressure conditions 70 which will not only tend to preserve a uniform surface finish throughout each sheet, but will also have the effect of expelling and excluding air from adjacent the paper, in a manner to check any tendency toward a loss 75 of uniformity in the degree of the dampness of the paper in different portions thereof.

By the practice of the method or art of my invention, the paper, during the entire period in which the various impressions are made thereon, is kept under conditions which 80 will prevent such expansion and contraction thereof as would result in such distortion as would necessitate a refinishing of the paper after the final impression has been made thereon.

To facilitate the practice of my method or art, I employ a special apparatus which may be associated with the collecting mechanism of a printing press. This apparatus is so constructed as to receive the printed sheets 90 directly from said collecting mechanism and to subject them to the various steps of the method or art under conditions which will secure the desired results. By the use of this apparatus, each sheet, after it is 95 printed, will have the opposite sides thereof presented to a surface, which will prevent offsetting of the ink and the escape of moisture from the sheet. At the same time the apparatus is so constructed as to insure the 100 application of the desired light pressure to each sheet, this pressure being uniform as to all sheets delivered by said collecting mechanism. At the same time, any air which may be pocketed between the printed sheet 105 and this other sheet, will be expelled therefrom.

The apparatus is so constructed as to be

2
capable of such adjustment as will synchronize it under various conditions of use with the functionings of the collecting mechanism. Other characteristics of this apparatus will appear from the accompanying drawings, and the detailed description of said apparatus herein contained.

The invention consists in a method or art of conditioning printed paper, consisting in 10 the novel steps and practices, and in an apparatus for the practice of said method or art, embodying therein the novel features of construction and combination of parts, all as hereinafter set forth and described 15 and more particularly pointed out in the claims hereto appended.

Referring to the drawings, Figure 1 is a side elevation of an apparatus especially designed for the practice of 20 the method or art of my invention; and

Fig. 2 is a plan view of a portion thereof.

Like letters refer to like parts in both of said views.

In the practice of my method or art, each 25 sheet of dampened paper, after it has received an impression from a planographic, or an engraved, intaglio, or under-surface printing plate, is inserted between opposed surfaces having a coating of a non-fluid substance, insoluble by the damping fluid with 30 which the paper is saturated, and having no affinity for the oily or greasy vehicle of the ink. These surfaces are afforded by a continuous strip or web of paper, or other flexible material, coated upon both sides with 35 ceresin wax, Japan wax, paraffin wax, or other analogous material having no affinity for the vehicle of the ink. The coating of this material presents a substantially continuous surface, closing the pores of the 40 paper, or other material, to an extent to exclude air from the printed, dampened sheet, and prevent the escape of moisture therefrom. In this manner offsetting of the ink 45 upon said surface and the drying of the printed sheet, is prevented.

To avoid distortion of the printed sheet with a resultant necessity for refinishing, I subject it to a continuing uniform pressure 50 applied through the coated paper, or other flexible strip, which pressure is sufficient to keep the printed sheet, and said strip of paper or other material, perfectly smooth, while being insufficient to smut or spread 55 the lines of the imprint. By keeping the printed paper, and said strip, smooth, I avoid the formation of air pockets adjacent the surface of the paper, or of air ducts resulting from creases, cracks or folds in the 60 paper, and at the same time am enabled to expel any air imprisoned between the printed paper and said strip, which might have a tendency to dry isolated spots of the surface 65 of the paper. Furthermore, the application of a slight pressure will have the effect of

diffusing the fluid with which the paper is dampened, throughout the entire body of the paper, and maintain a uniform dampened condition of the paper.

To facilitate the rapid handling of the 70 printed sheets as they leave the collecting mechanism of a press, I wind a strip of the coated paper, or other material, into a roll, while maintaining a tensioning stress upon said strip, the sheets of printed paper being 75 laid upon this strip and wound within the roll while it is being formed. After a full length of the coated strip, or other material, has been wound into a roll, the roll, with the printed sheets therein, is allowed to stand 80 until said sheets are required for a succeeding run thereof through the press, thus storing all of the sheets under conditions which will prevent their drying between runs.

The tensioning stresses not only keep the 85 coated strip of paper, or other material, taut and smooth, but will exert sufficient pressure upon the printed, dampened sheets, to keep them flat and smooth, and in addition thereto, will squeeze out any air which may be imprisoned between the printed sheet and the strip as the printed sheet is gradually wound within the roll. 90

Under some conditions, repeated runs of 95 the paper through a press, will afford opportunity for the dampened sheets to lose some of their moisture, but I have found that this may be restored by slightly dampening either, or both surfaces of the coated strip. 100

The width of the coated strip or paper, or other material, should be such as to project beyond the edges of the printed sheet to an extent to prevent the entrance of air adjacent the edges of said printed sheet. 105

In addition to preventing the loss of moisture from the dampened sheet, the practice of my method or art will tend to secure and maintain a uniform diffusion of this moisture in the sheet, preserving the desired 110 low condition of the paper.

In the accompanying drawings, I have illustrated an apparatus by means of which the method or art of my invention may be automatically carried out. This apparatus 115 comprises a reel *a* removably mounted in suitable bearings *b*, so as to permit the removal of one reel with the dampened paper and the protecting strip thereon, and the substitution of another reel to permit the 120 continued collection and storage of the printed sheets.

Removably mounted in suitable bearings in the frame *c*, is a supply reel *d* for the coated strip of paper, or other material, *e*. 125 The strip *e* passes over a suitable guide roller or rollers *f*, from the reel *d* to the reel *a*.

The frame *c* carries tapes *g*, said tapes being adjacent the reach of the strip *e* between 130

the guide roller *f* and the reel *a*. The tapes *h* convey the sheets from the delivery cylinder of the printing press to the tapes *g*. By this mechanism each printed sheet, as it is delivered from the printing press, is laid flat upon the strip *e*, being conveyed thereby to the reel *a* upon which the strip *e* is wound, one surface of the printed sheet being engaged with the portion of the strip *e* upon which it is laid, and the other surface thereof being brought into engagement with a previously wound portion of said strip.

The reel *a* is continuously rotated by means of a friction drive mechanism, so constructed as to permit a gradual reduction in the speed of rotation of the reel *a* with the increased diameter of the roll as it is formed thereon. This mechanism, in the form of the invention shown, comprises a friction wheel *i* adapted to actuate the reel *a*, which wheel bears upon two friction wheels *j* and *k*, driven by means of gears *j'* and *k'*, carried by the wheels *j* and *k* respectively, which gears are in mesh with a gear wheel *m* rotated by a friction disk *n*. The gear *m* and disk *n* are idly mounted upon a shaft *m'*. One end of said shaft *m'* carries a bearing *m*² for a shaft *p*, having splined, or otherwise slidably mounted thereon, a friction wheel *q* bearing upon, and adapted to have movement radially of, the disk *n*. The shaft *p* carries a bevel gear *p'* meshing with a gear *p*², driven by means of a chain and sprocket mechanism *p*³, from any desired source of power, synchronized with the functionings of the sheet delivering mechanism of the printing press.

The gear *m* and friction disk *n* are connected by means of studs *n'* carried by the disk *n*, and projecting through suitable openings in the gear *m*. Springs *o* encircle said studs, and thrust the disk *n* into the desired frictional engagement with the wheel *q*, and automatically take up any wear upon either of said members.

The friction wheel *i* bears upon the wheels *j* and *k*, which are flanged as shown, the said wheel *i* being mounted in fixed bearings, and carrying a pintle bearing *i'* engaging the reel *a*.

The strip *e* is placed under a uniform tension by means of a friction wheel *r* carried by the reel *d*, and a band brake *r'* set by means of the spring *r*² coöperating therewith.

To permit a variation in the speed of drive of the reel *a*, I groove the hub of the friction wheel *g*, and provide a rocking arm *s* having suitable pins *s'* acting in said groove, said arm being actuated by means of the gear *s*² carried thereby, and an actuating gear *t* meshing therewith, and having a crank arm *t'*.

The standards *u* supporting the friction drive mechanism, one of said standards be-

ing arranged at each side of the machine, are provided with an adjustable head *u'* supporting the shaft *m'*, said head being adjustably mounted upon said standards by means of the rack and pinion mechanism *v*, which may be actuated by the handle *v'* to cause the friction wheels *j* and *k* to be moved into, or out of, engagement with the wheel *i*.

In the accompanying drawings, the printed sheets of paper are indicated at *w*.

The operation of the herein described apparatus is substantially as follows:—

As each sheet receives an imprint, it is conveyed by the tapes *h* toward the frame *c* and delivered to the tapes *g*. From said last named tapes, each sheet is laid upon the reach of the strip *e* between the guide roller *f* and the reel *a*. The tapes *g* and *h* are continuously actuated in the usual and well known manner, the strip *e* being moved at substantially the same rate of speed by the mechanism *p*³, the shaft *p* and the friction drive mechanism actuated thereby. As the strip *e* is wound upon the reel *a*, the sheets *w* will be wound within the said strip, the desired tension upon the strip, sufficient to keep it perfectly smooth and apply a light pressure to the sheets *w*, being secured by means of the band brake *r'* acting upon the wheel *r*.

As the diameter of the roll upon the reel *a* gradually increases, the friction wheel *q* may be moved radially of the disk *n*, upon the shaft *p*, by means of the lever *s* and its actuating mechanism, thus permitting the desired reduction in the R. P. M. of the reel *a*, to compensate for a tendency toward an increase in the rate of travel of the strip *e* by reason of the gradual increase in the diameter of the roll upon said reel. By utilizing a friction drive, such slippage may occur as to minimize this tendency toward an increase of the rate of travel of the strip *e*, however.

If it be desired to run a press without actuating the reel *a*, as during the make-ready, the friction wheels *j*—*k* are dropped by means of the rack and pinion mechanism *v* and its operating handle *v'*, sufficiently to move the wheels *j*—*k* out of the operative relation with the wheel *i*.

By spacing the reel *a* away from the tapes *g*, sufficient time is allowed to inspect the imprints, while they are traveling upon the strip *e*.

An apparatus having the mode of operation heretofore described, is capable of performing the various steps of the method or art of my invention, automatically, and has the additional advantage that it requires no manual handling of the printed sheets and will receive the sheets and treat them at a speed commensurate with the speed of operation of the printing press.

It is not my intention to limit the invention to the precise details of construction shown in the accompanying drawings, it being apparent that such may be varied without departing from the spirit and scope of the invention.

Having described the invention what I claim as new, and desire to have protected by Letters Patent, is:—

- 10 1. The herein described method or art of conditioning printed paper, consisting of bringing a printed, dampened sheet of paper between two surfaces, each coated with a substance having no affinity for the oily or greasy vehicle of the ink and rendering said material impenetrable to atmosphere and substantially non-absorbent, applying pressure to said paper while between said surfaces, whereby air will be expelled from adjacent the surface of said paper, and allowing said sheets to stand in contact with said surfaces until required for another run through the press, whereby the ink of said paper is prevented from offsetting upon said surfaces, and the moisture is retained in, and is diffused throughout, said paper.
- 15 2. The herein described method or art of conditioning printed paper, consisting of bringing a printed, dampened sheet of paper between two surfaces, each coated with a substance having no affinity for the oily or greasy vehicle of the ink and rendering said material impenetrable to atmosphere and substantially non-absorbent, maintaining said coated material smooth while bringing the dampened paper in contact therewith applying pressure to said paper while between said surfaces, whereby air will be expelled from adjacent the surface of said paper, and allowing said sheets to stand in contact with said surfaces until required for another run through the press, whereby the ink of said paper is prevented from offsetting upon said surfaces, and the moisture is retained in, and is diffused throughout, said paper.
- 20 3. The herein described method or art of conditioning printed paper, consisting of winding succeeding printed, dampened sheets of paper within a strip of material having the opposite sides thereof coated with a substance having no affinity for the oily or greasy vehicle of the ink and rendering said material impenetrable to atmosphere and substantially non-absorbent, applying pressure to said paper through said material, whereby air will be expelled from adjacent the surface of said paper, and allowing said sheets to stand in contact with said material until required for another run through the press, whereby the ink of said paper is prevented from offsetting upon said material, and the moisture is retained in, and diffused throughout, said paper.
- 25 4. The herein described method or art of conditioning printed paper, consisting of winding succeeding printed, dampened sheets of paper within a strip of material having the opposite sides thereof coated with a substance having no affinity for the oily or greasy vehicle of the ink and rendering said material impenetrable to atmosphere and substantially non-absorbent, applying tensioning pressure to said material while the sheets are being wound therein, whereby air will be expelled from adjacent the surface of said paper, and allowing said sheets to stand in contact with said material until required for another run through the press, whereby the ink of said paper is prevented from offsetting upon said material, and the moisture is retained in, and diffused throughout, said paper.
- 30 5. The herein described method or art of conditioning printed paper, consisting of bringing a printed, dampened sheet of paper between two surfaces, each coated with a substance having no affinity for the oily or greasy vehicle of the ink and rendering said material impenetrable to atmosphere and substantially non-absorbent, applying pressure to said paper while between said surfaces, whereby air will be expelled from adjacent the surface of said paper, renewing moisture in said sheets by dampening at least one of said surfaces, prior to bringing the sheets in engagement therewith, and allowing said sheets to stand in contact with said surfaces until required for another run through the press, whereby the ink of said paper is prevented from offsetting upon said surfaces, and the moisture is retained in, and is diffused throughout, said paper.
- 35 6. An apparatus for conditioning printed paper embodying therein a winding reel adapted to have wound thereon, a strip of material having the opposite sides thereof coated with a substance having no affinity for the oily or greasy vehicle of the ink, and rendering said material impenetrable to atmosphere and substantially non-absorbent, a support for a supply reel of said strip, and means whereby said winding reel may be rotated to form a roll of said strip, with printed, dampened sheets of paper inclosed therein.
- 40 7. An apparatus for conditioning printed paper embodying therein a winding reel adapted to have wound thereon, a strip of material having the opposite sides thereof coated with a substance having no affinity for the oily or greasy vehicle of the ink, and rendering said material impenetrable to atmosphere and substantially non-absorbent, a support for a supply reel of said strip, means associated with the delivery mechanism of a press, whereby succeeding printed sheets will be laid upon said strip intermediate said winding reel and said supply reel, and means whereby said wind-

ing reel may be rotated to form a roll of said strip, with printed, dampened sheets of paper inclosed therein.

8. An apparatus for conditioning printed paper embodying therein a winding reel adapted to have wound thereon, a strip of material having the opposite sides thereof coated with a substance having no affinity for the oily or greasy vehicle of the ink, and rendering said material impenetrable to atmosphere and substantially non-absorbent, a support for a supply reel of said strip, means associated with the delivery mechanism of a press, whereby succeeding printed sheets will be laid upon said strip intermediate said winding reel and said supply reel, means whereby said winding reel may be rotated to form a roll of said strip, with printed, dampened sheets of paper inclosed therein, and means whereby the speed of rotation of said winding reel may be varied to accord with the variance in the diameter of the roll of strip thereon, to insure a substantially uniform rate of travel of said strip.
- 25 9. An apparatus for conditioning printed paper embodying therein a winding reel adapted to have wound thereon, a strip of material having the opposite sides thereof coated with a substance having no affinity for the oily or greasy vehicle of the ink, and rendering said material impenetrable to atmosphere and substantially non-absorbent, a support for a supply reel of said strip, means whereby said winding reel may be rotated to form a roll of said strip, with printed, dampened sheets of paper inclosed therein, and means applying a tensioning pressure to said strip of material as it is being wound upon said winding reel.
- 40 10. An apparatus for conditioning printed paper embodying therein a winding reel adapted to have wound thereon, a strip of material having the opposite sides thereof coated with a substance having no affinity for the oily or greasy vehicle of the ink, and rendering said material impenetrable to atmosphere and substantially non-absorbent, a support for a supply reel of said strip, means whereby said winding reel may be rotated to form a roll of said strip, with printed, dampened sheets of paper inclosed therein, and means whereby the speed of rotation of said strip may be varied to accord with the variance in the diameter of the roll of strip thereon, to insure a substantially uniform rate of travel of said strip.
- 45 11. An apparatus for conditioning printed paper embodying therein a winding reel adapted to have wound thereon, a strip of material having the opposite sides thereof coated with a substance having no affinity for the oily or greasy vehicle of the ink, and rendering said material impenetrable to atmosphere and substantially non-absorbent, a support for a supply reel of said strip, a friction wheel adapted to apply power to said winding reel, a friction disk, a plurality of friction wheels operatively engaging the friction wheel applying power to said reel, gears connecting same with said friction disk, a friction wheel coöperating with said disk, and means whereby said last named friction wheel may be moved radially of said disk to vary the speed of rotation thereof, and of said reel.
- 50 12. An apparatus for conditioning printed paper embodying therein a winding reel adapted to have wound thereon, a strip of material having the opposite sides thereof coated with a substance having no affinity for the oily or greasy vehicle of the ink, and rendering said material impenetrable to atmosphere and substantially non-absorbent, a support for a supply reel of said strip, a friction wheel adapted to apply power to said winding reel, a friction disk, a plurality of friction wheels operatively engaging the friction wheel applying power to said reel, gears connecting same with said friction disk, a friction wheel coöperating with said disk, and means whereby said last named friction wheel may be moved radially of said disk to vary the speed of rotation thereof, and of said reel, and means whereby the friction wheel driving said winding reel and the friction wheels coöperating therewith, may be separated to prevent actuation of said reel.

In witness whereof I have hereunto affixed my signature this 23 day of July, 1918, in the presence of two subscribing witnesses.

PETER AITCHISON.
